(57) **CLAIM**

The ornamental design for a dispensing closure, as shown and described.

DESCRIPTION

FIG. 1 is a top perspective view of the dispensing closure in a closed position;

FIG. 2 is a top perspective view of the dispensing closure according to FIG. 1 in an open position;

FIG. 3 is a front view of the dispensing closure according to FIG. 1;

FIG. 4 is a back view of the dispensing closure according to FIG. 1;

FIG. 5 is a left or right side view of the dispensing closure according to FIG. 1, the two views being identical;

FIG. 6 is a top view of the dispensing closure according to FIG. 1; and,

FIG. 7 is a bottom view of the dispensing closure according to FIG. 1.

The broken lines immediately adjacent the shaded areas represent the bounds of the claimed design and all other broken lines depict unclaimed environment; the broken lines form no part of the claimed design.
